UNITED STATES PATENT OFFICE.

ALEXANDOR WAIDICH, OF CHICAGO, ILLINOIS.

LAUNDRY BAG.

Application filed October 21, 1922. Serial No. 596,111.

To all whom it may concern:

Be it known that I, ALEXANDOR WAIDICH, a citizen of the United States, residing at Chicago, in the county of Cook and State 5 of Illinois, have invented new and useful Improvements in Laundry Bags, of which the following is a specification.

This invention relates to laundry bags or clothes hampers, and an object of the invention is to provide a neat appearing compact container for either soiled or clean clothes, which may be supported from a suitable support and comprises front and rear sides connected by foldable webs and having their 15 upper open edges reinforced by reinforcing poles.

Another object of the invention is to provide a novel form of catch for holding the upper edges of the front and rear sides of 20 the bag in closed position.

Other objects of the invention will appear in the following detailed description taken in connection with the accompanying drawing wherein:—

25 Fig. 1 is a front elevation of the improved bag.

Fig. 2 is a side elevation of the bag.

Fig. 3 is an enlarged detail vertical section taken on the line 3—3 of Fig. 1.

30 Fig. 4 is a detail cross section taken on the line 4—4 of Fig. 1.

Fig. 5 is a front elevation of a modified form of the laundry bag.

Referring more particularly to the drawings, the improved laundry bag comprises 35 the clothing container or bag 1 which includes a front side 2 and rear side 3. The sides 2 and 3 are connected by the edge pieces 4, which are creased longitudinally 40 as shown at 5 in Fig. 4 of the drawings to permit the front and rear sides 2 and 3 to be moved towards each other for closing the bag structure. The edges of the front and rear sides and the edges of the end pieces 4

45 are stitched together and bound by suitable binding 6 of any suitable material to increase the strength and add to the appearance of the bag. The front and rear sides preferably have their upper portions cut 50 away as shown at 8 to add to the attractiveness of the appearance of the device, and they are hemmed as shown at 9 and 10 respectively, the hems encircling or receiving rods or poles 11 and 12 respectively, the ends 55 of which may be ornamented as shown at 13.

In the preferred form as shown in Figs.

1 to 4 of the drawings suspending cord 14 is connected to the ends of the rod 12 and it has a loop 15 formed thereon which is adapted to engage over any suitable type 60 of support as indicated at 16. Suitable decorative tassels 17 are carried by the rod 11 and by the suspending cord 14.

A sheet metal clasp 19 is attached to the rod 11 in any suitable manner such as by 65 screws 20 and it extends below the rod, as clearly shown in the drawings. The upper end 21 of the clasp 19 is curved for engaging over the bar or rod 12 for holding the bag closed and when it is desired to open the 70 bag the curved end 21 is removed from the bar or rod 12, which permits the front side 2 of the bag to swing outwardly as shown in Fig. 2 of the drawings. A finger tab 22 is stitched to the front side 2 preferably at 75 the stitching of the hem 9.

By particular reference to Figs. 1 and 3 of the drawings it will be noted that the back 3 is slightly larger than the front 2 so that the rod or bar 11 will engage beneath the rod or bar 12 when the bag is 80 closed providing a flat, neat appearing bag structure.

In Fig. 5 of the drawings a modified form of the bag is shown which modified form 85 is similar to the preferred form in every respect with the exception of the manner of supporting or suspending of the bag. In the modified form the rod or bar 12' which is carried at the upper edge of the rear side 90 of the bag is extended beyond the ends of the rod or bar 11' and has its terminals extended transversely as shown at 30 to provide substantially hook shaped terminals. Projections 31 are also formed upon the rod 95 or bar 12' in proper spaced relation to the extensions 30, cooperating therewith in forming a socket for engagement over a suitable support as shown at 32, for supporting the bag directly from the supports 100 32 and the bar 12'.

It is, of course, to be understood that the invention may be constructed in other manners and the parts associated in different relations and, therefore, I do not desire to 105 be limited in any manner except as set forth in the claims hereunto appended.

Having thus described my invention what I claim is:

1. In a laundry bag, front and rear sides, 110 foldable ends connecting said sides, the upper edges of said front and rear sides

being free from connection, bars carried by said free edges, and a clasp carried by one of said bars adapted to engage the other bar, said front side being slightly shorter than the rear side whereby the bar carried by the front side will lie beneath and in parallel relation to the bar carried by the rear side.

2. In a laundry bag, front and rear sides, foldable ends connecting said sides, the upper edges of said front and rear sides being free from connection, bars carried by said free edges, and a clasp carried by one of said bars adapted to engage the other bar, said front side being slightly shorter than the rear side whereby the bar carried by the front side will lie beneath and in parallel relation to the bar carried by the rear side, and means carried by the bar car-

ried by the rear side for supporting the 20 bag.

3. In a laundry bag, front and rear sides, foldable ends connecting said sides, the upper edges of said front and rear sides being folded upon themselves and stitched to 25 the body portion thereof to form transverse pockets, bars arranged within said pockets, a clasp carried by one of said bars and adapted to yieldably engage the other bar, 30 said front side being slightly shorter than the rear side whereby the bar carried by the front side will lie beneath and in parallel relation to the bar carried by the rear side.

In testimony whereof I affix my signature. 35

ALEXANDOR WAIDICH.
